In Germany April 14, 1934

7 Claims. (Cl. 179—18)

For the control of numerical impulse trains in long distance communications, especially in telephone systems for any purpose whatsoever, for example for reckoning the calculated fee for an established connection, switching on to another line, preventing undesirable connections, etc., a discriminator is used which is placed in the calling path or is capable of being connected to the path and which is controlled by the numerical impulse trains transmitted from the station making the call. If the first of the numerical impulse trains operating over the connecting point of a discriminator are not to exercise control, but only the control of the later trains, for example the third or fourth train is desirable, it is necessary either to allow all the impulse trains, including the non-controlling ones to act upon the discriminating device or for the latter to suppress the first non-controlling impulse trains. Such arrangements can, however, be very unsatisfactory in some circumstances, for it may be necessary in the first case to provide several discriminators for the reception of these impulse trains, or discriminators with large contact banks and several sets of wipers, or several relay groups through relay selectors. But the arrangements by which the non-controlling impulse trains exert noninfluence on the discriminating device may be unsatisfactory particularly when it is a question of suppressing several impulse trains, for this is only possible by correspondingly complicated control and change-over switching, which generally necessitates a considerable number of control relays.

The present invention now makes possible a control of the first numerical impulse trains, which become active after the partial establishment of the connection by the simplest means whereby the first non-controlling impulse trains passing through the connecting point of the discriminator influence the latter only in a definite way independent of the number of the impulses, and on the termination of these non-controlling numerical impulse trains, switching means begin to come active which bring the discriminator under the influence of further individual numerical impulse trains transmitted from the calling station.

The arrangement according to the invention can now be set up so that, in a definite call direction the number of the non-controlling impulse trains can be increased or diminished whereby the switching means, depending on the call number, e. g., depending upon the operation of a numerical impulse receiver in the call route, produces such switching as to bring the discrimina-

tor sooner or later under the influence of the numerical impulses transmitted from the calling station.

Furthermore, the arrangement according to the invention can be so set up that the settings of the discriminator used for the supervising of the latter by non-controlling impulses are also employed for the control of the numerical impulse trains.

In the drawings some embodiments of the invention are shown, and Fig. 1 shows an embodiment of the invention used for a telephone system with automatic operation. The discriminating device influenced by the numerical impulse trains effects different switchings according to the value of the individual numerical impulse trains, corresponding to the selected call direction or the call facility of the calling station, which effects the operation of the meter corresponding to the fee for an established connection; or the switching over of the calling subscriber from the seized line to another line; or the prevention of a definite line being connected by the call of a subscriber not entitled to this connection. It is evident that the invention can find application for any similar object whatsoever, for example, the connection of an operator in the case of calls in a particular direction, the switching of control apparatus for measuring or statistical work, etc.

Figs. 2 to 4 show further modes of application for the control of the discriminator.

The manner of operation of the form shown in Fig. 1 will be explained first.

The discriminating device ML consisting of a stepping switch is attached to a first group selector (I. G. W.). This group selector can be reached by two different routes, one by the path a_1, b_1, c_1, d_1 from the subscribers who are entitled to set up a call in all directions, and the other by a_2, b_2, c_2, d_2 , from subscribers who are only entitled to establish calls in one fixed direction. In the following description the call which is established by a subscriber entitled to all calls is first illustrated.

The calling subscriber seizes the first group selector I. G. W. over the circuit shown a_1, b_1, c_1, d_1 , whereby relay C can energize over lead c_1 and its winding 1 and the off normal contact 1KGW of the group selector. Relay C is fitted with a delayed armature make and break. It accordingly closes its contact $2c$ slowly. Simultaneously with the seizing of the first group selector I. G. W. the calling subscriber's talking line leads which are not shown, were connected with leads a_1 and b_1 . According to the line

loop shunt relay A is subjected to the microphone feeding current of the calling subscriber, through windings I and II. This energizes a short circuit relay V2 at its contact 3a. The 5 contact 2c being closed the following circuit is set up: — pole of contact 2c, winding II of relay C, contact 3a, winding I of relay VI+pole of battery. Relay VI prepares the switching device of the group selector for operation by the 10 numerical impulse train transmitted from the calling station, and so long as it is energized regulates the group selector in the known manner.

The driving magnets controlling the group 15 selector are not shown in the diagram. The control of the group selector can take place in any way desired. It has been omitted since it is not concerned with the object of the invention.

The first impulse train transmitted from the 20 calling station activates the group control of I. G. W. At the first numerical impulse of this train contact 3a is opened and 4a is closed. In consequence the short circuit of relay V2 is removed; this therefore energizes and closes 25 through contact 5v2 the following circuit for the rotary magnet Dm1 of the discriminator M1: —+ pole of battery, magnet Dm1, wiper 6, contacts 7, 5v2, 8v1, 9hr, — pole of battery. The rotary magnet Dm1 promotes the advancement 30 of wipers 6 and 10 of the discriminator to the next switch position. The wiper 6 then stands on contact 11. At the end of the impulse train as relay A again remains energized for some time, relay V2 releases closing its contact 12v2 35 and thereby provoking the renewed energizing of the rotary magnet Dm1 through contact 11. Wipers 6 and 10 thereupon proceed to the next switch position, in which wiper 6 stands on contact 13.

40 After the setting of the group selector by the first numerical impulse train there follows the automatic selection of a free connecting lead of the selected call direction. On finding one the winding I of test relay P is connected to the 45 + pole of the battery through contact 35v1, the relay energizes across wiper 36; protects the selected lead against selection by another seeking group selector by short circuiting the high resistance winding I at its contact 10p, and connects 50 the speech leads to contacts 32p and 37p which makes possible the transmission of further numerical impulse trains from the calling station to the arranged numerical impulse receiver through impulse receiving contact 11a.

55 It is thus clear that the discriminator being independent of the number of the first train forming impulses was only influenced in a set way. That is to say, it only advances two steps, the first at the beginning of the impulse train 60 and the second at the end of this.

In the same way the subsequent switching of wipers 6 and 10 is performed at the beginning and end of the second impulse train. At the 65 end of the second impulse train wiper 6 rests on contact 14. If the third impulse train is to be operative relay V2 again promotes the further switching of the discriminator by energizing rotary magnet Dm1. The wiper 6 now comes to contact 15.

70 These three impulse trains are for setting up the connection, not for controlling. When now at the end of this third impulse train relay V2 deenergizes, a winding I of relay Hr is thereby connected through the circuit closed by contact 75 12v2. This winding is of such a high resist-

ance that the rotary magnet Dm1 cannot energize in this circuit. Thus a further switching of the discriminator at the end of the last non-controlling impulse train does not take place. Relay HR is now connected through its contact 5 16hr to contact 17r1 and prepares over its winding II a locking circuit and later, at contact 18hr prepares a circuit for the driving magnet Dm1 of the discriminator in which the latter is advanced correspondingly to the number of impulses forming the fourth impulse train. This circuit which is closed at each deenergizing of relay A, runs as follows: + pole of battery, rotary magnet Dm1, contact 18hr, 19a, 20v1, 26f, + pole of battery. 10 15

Suppose that the fourth impulse train consists of five impulses. Wiper 10 has been set on contact 21. Suppose also that only one impulse train is to perform the controlling, so that after the fourth impulse train has operated, 20 a renewed control of the discriminator by the further impulse train required for the establishment of the calling direction, is not necessary. But obviously the arrangement can also be made so that with several impulse trains the 25 discriminator is stepped on correspondingly to the number of each train building impulse. In order to prevent further stepping of the discriminator at the end of the fourth impulse train, the following circuit is closed through 30 contact 22v2 which closes at the end of this train: + pole of battery, contacts 22v2 and 23hr, wiper 24, one of the contacts 25, auxiliary relay F, + pole of battery. The auxiliary relay F breaks at contact 26f the circuit through which 35 the rotary magnet Dm1 of the discriminator is operated by the impulses of the fourth train transmitted from the calling station.

The call established by the calling station is an 40 expensive one. But it is entitled to this call since group selector IGW has been reached through seizing lead C1. Relay BR is thus not excited. During the conversation no switching operation 45 passes the discriminator through this connection. Firstly at the end of the conversation an activation of the meter of the calling station results, corresponding to the charge for the connection established. In order to do this an assessor AB is provided whose bank contacts are wired to the bank contacts of the discriminator, which are 50 wiped by the wiper 10 of the discriminator. Contact 21 on which the wiper 10 rests by the above connection, is thus connected to bank contact 27.

The calculation of the fee by the meter of the calling subscriber now proceeds in the following 55 way: at the end of the connection the calling subscriber replaces his receiver. In consequence relay A becomes deenergized and winding II of relay C short circuits at its contact 4a. Relay C releases, opens its contact 28c and 29c closed during the connection and closes its contact 30c and 31c. Through contact 30c and 32p the winding II of relay VI is connected to the wiper 33 of the discriminator IGW and thence to the lead 34 connected to it. As it is a question of a paying call the + pole of the battery is connected to this lead in some way or another, for example through the final selector, in consequence of which relay VI since it is fitted with a delayed armature release and does not immediately deenergize on the opening of contact 2c, still remains energized. The group selector IGW also remains set, since the + pole of the battery through contact 35v1 remains connected to relay P and thereby to testing wiper 36 of the group selector. Relay ZR 70 75 80 85 90 95 100

makes contact over contacts **31c** and **31p** and the wiper **38**, with the lower (39) of the leads connected to the group selector since in the latter part of the connecting line the — pole is connected to this lead this relay is energized and promotes the operation of the assessor and thereby the transmission of the meter impulses to the meter of the calling subscriber.

By energizing, relay **ZR** closes its contact **40zr** which establishes the following circuit: + pole of battery, contacts **41c**, **40zr**, driving magnet **Dab** of the assessor, contacts **42c**, **43p1**, **44v1**, **45p**, — pole of battery. The rotary magnet **Dab** energizes and the assessor advances a step. Through contacts **46dab** and **47v1** the relay **E** energizes which connects the + pole of the battery at the contacts **48c** to the incoming lead **c1** and thereby on account of the amplification of the current over these leads, activates the meter of the calling subscriber. Relay **E** also opens the circuit of the magnet **Dab** at its contact **42e**. This deenergizes and at contact **46** opens the circuit of relay **E** which in its turn closes the circuit for the magnet **Dab**. This play between **Dab** and relay **E** continues sending an impulse over lead **C1** with every energizing of relay **E**, until relay **P1** is energized by wiper **48** reaching contact **27**: + pole of battery, contact **49hr**, wiper **10**, contacts **21** and **27**, wiper **48**, relay **P1** — pole of battery. Relay **P1** opens the circuit for the driving magnet **Dab** at contact **43p1**. The assessor is brought to rest. The meter of the calling subscriber has been advanced a number of steps corresponding to the fee for the call completed.

The energizing of relay **P1** initiates furthermore the release of the group selector, the discriminator, and the assessor by short circuiting relay **P** at contact **50 p1**. This releases, opens contacts **32p** and **31p** so that now relays **V1** and **ZR** also release. The release of relay **V1** allows in a manner with which we are not concerned the release of the group selector and also the release of the pre-selecting mechanism placed in front of the group selector the release of the pre-selector taking place by the opening of contact **51v1** whereby the + pole of the battery is removed from lead **C1**.

Furthermore the following circuit is established for rotary magnet **Dm1** at contact **52v1**: + pole of battery, magnet **Dm1**, off normal contact **53km1**, contact **52v1**, breaking switch **54**, — pole of battery. The discriminator is switched to its rest position in which it remains since contact **53km1** is open. The closing of contact **55v1** results in the switching of the assessor to the rest position and so in the following circuit + pole of battery, contacts **41c**, **56p**, magnet **Dab**, contact **57kab**, breaking switch **58**, contact **55v1**, — pole of battery, the assessor reaches its rest position and remains there since contact **57kab** is then open.

The case may now be considered in which the same call which has been established by an entitled subscriber is sought by a non-entitled subscriber. For this call the non-entitled subscriber can only reach the group selector over the path **a2** to **b2** since the entry is already selected.

In the seizing lead **c2** lies relay **BR** which energizes and closes its contacts **59br** and **60br**. If by the fourth impulse train wiper **10** is again set on contact **21**, since contact **59br** is closed relay **P** is short-circuited (+ pole of battery, contact **49hr**, wiper **10**, contacts **21** and **59br**, wiper **36**). Relay **P** thus releases. It opens contacts **32p** and **31p**, thereby preventing the further re-

ception of numerical impulses, and closes among others its contact **61p** and whereby a buzzer is connected to winding **III** of relay **A** since relay **HR** also energizes and the contact **62hr** is closed. The calling subscriber receives a buzzing signal and knows from this that he cannot obtain his desired call. By using a special buzzer which differentiates between free and engaged signals the calling subscriber can tell that he has tried to establish a call which is engaged.

If the calling subscriber now replaces his receiver the call is not charged for, because the circuit for the rotary magnet of the assessor cannot be completed since contact **45p** is open. Consequently relay **V1** does not remain energized by its winding **II** since contact **32p** is open. Later also no energizing of relay **ZR** takes place on account of contact **37p** being open. After relay **A** deenergizes, relay **V1** also releases and allows of the release of the group selector, sets free the preselecting device which had kept this seized, and releases the discriminator.

If the fourth impulse train transmitted from the calling station, independent of whether it concerns an entitled subscriber or a non-entitled subscriber, consisted of eight impulses, the wiper **10** of the discriminator **ML** was placed on contact **63**. This contact **63** is connected with contact **64** of the assessor. Since contact **63** is the second contact in the bank, reckoned from the rest position of the discriminator, it is clear that those contacts on which the wiper of the discriminator has been set by non-controlling impulse trains, can also be connected by the control of impulse trains. The driving magnet **Dm1** of the discriminator is not influenced since the wiper **6** comes into contact for the second time with contact **11**, because the contact **9hr** is open and hence the completion of the circuit for the driving magnet at the end of the fourth impulse train cannot take place.

The registering of the call is effected in the way described above.

If wiper **10** is set on contact **65** through the fourth impulse train controlling the discriminator, it is characteristic that the calling station must be switched over to another line, for example to a final selector belonging to a particular group. Accordingly relay **U** is energized over this contact of the discriminator at the end of the impulse train and thence after the release of relay **V2** and the closing of contact **66v2** and promotes the subscriber's reversal in the known way which we are not here concerned with, through closing contact **67u** over lead **d1**, or **d2**, according to which class the subscriber of the calling station belongs.

Cases can now be considered, Fig. 4, having a definite call direction which result in controlling by the second impulse train. This is attained by the contact **68kgw** closing after the setting of the first group selector on the contact group concerned e. g. the fifth contact group. On the deenergizing of relay **V2** and the closing of contact **69v2** relay **HR** immediately energizes through its winding **II** and prepares the circuit for the driving magnet **Dm1** of the discriminator, over which this is already operated by the second impulse train.

In the example just described the discriminator is stepped on two places by each of the non-controlling impulse trains, one step occurring at the beginning and the second at the end of the impulse trains. It is also possible, however for the discriminator to be advanced only one step by each of the non-controlling impulse trains. This

is for example readily possible in the present embodiment, if the step switching device serving for a discriminator has an indirect drive, that is to say a drive by which the advancement of the wiper first occurs on the deenergizing of the rotary magnet. In this case the rotary magnet would receive a current by the closing of contact 5v2 at the beginning of an impulse train, but an advancement of the wiper does not result from this, but first occurs when at the end of the impulse train its circuit is broken by the opening of contact 5v2.

The advancement of the discriminator through only one step with every noncontrolling impulse 15 can also be accomplished with stepping switches which immediately make one step on the energizing of the driving magnet. Figures 2 and 3 show the principle of two such examples of application. In these figures only the circuit for the discriminator is shown, and the individual parts of the circuit, which correspond to those of Figure 1 have the same reference characters.

Figure 2 shows an arrangement by which the advancement of the discriminator by one step occurs at the end of each noncontrolling impulse train. For this object a delayed relay V3 is provided which is operated through the energizing of relay V2 at the beginning of each impulse train, over its contact 80v2. Relay V3 closes its contact 30 83v3 and thereby prepares the energizing circuit for the magnet Dm1. When relay V2 releases at the end of the impulse train it closes its contact 82v2 and contact 80v2 opens. Since, however, relay V2 is provided with a delayed armature release, contact 83v3 remains closed for some time and the following circuit for the rotary magnet Dm1 is set up: + pole of battery, rotary magnet Dm1, wiper 6, contacts 81, 82v2, 83v3, 8v1, 9hr, — pole of battery. The discriminator is displaced by 40 1 space to prevent a further energizing of the rotary magnet in the second switching, when contact 83v3 will still be closed, wiper 6 is made in such a way that while moving from one contact to another it connects these two contacts together, a release of the rotary magnet Dm1 between two contacts and hence a renewed energizing on the second contact, when contact 83v3 will still be closed, is thus definitely prevented.

At the end of the second impulse train wiper 50 6 is brought to contact 84. The winding I of relay HR is connected to this but the former is first allowed to receive current at the end of the third impulse train. In order to prevent this winding receiving current after the advancement 55 of the discriminator at the end of the second impulse train when contact 83v3 will still be closed after the stepping operation of the discriminator, it is short circuited through a contact 85d_{m1} of the rotary magnet of the discriminator. Contact 83v3 opens so that Dm1 releases and the winding I of relay HR is connected. At the end of the third impulse train current flows through the winding on the closing of contact 82v2 and energizes relay HR. 60 Magnet Dm1 cannot, however, energize on account of its high resistance. Relay HR thus brings about the circuit change illustrated by Fig. 1.

Fig. 3 shows a mode of application in which 70 the advancement of the discriminator by one step occurs at the beginning of each noncontrolling impulse. For this purpose a relay V3 is provided which is slow to energize, this is activated by the energizing of relay V2 at the beginning of 75 the impulse train, over contact 90v2. Relay V2,

moreover, closed its contact 92v2 and thereby completed the circuit for Dm1: + pole of battery, rotary magnet Dm1, wiper 6, contacts 91, 92v2, 93v3, 8v1, 9hr — pole of battery. After a short time relay V3 energizes and opens contact 93v3 breaking the circuit just described. A double energizing of the rotary magnet at the beginning of an impulse train, when contact 93v3 will no longer be open after the switching operation, is prevented, in the same way as by 10 the arrangement of Fig. 2, in that the wiper 6, when resting in a position between two contacts connects the two together.

At the beginning of the third impulse train wiper 6 is stepped on to contact 94. This results in the energizing of relay HR which is connected to this contact, but not until the end of the third impulse train after the release of relay V2 the following circuit: + pole of battery, rotary magnet Dm1, wiper 6, contact 94, winding I of relay HR, contacts 12v2, 8v1, 9hr, — pole of battery. Relay HR thus effects the circuit change explained in the description of Fig. 1.

Fig 4 shows an arrangement by which it is possible to bring the discriminator under the influence of the impulse contact 19a as soon as the 25 end of the second numerical impulse train, when these have selected a definite call route. This is made possible by an auxiliary relay G which can be influenced through the wiper 38 and lead 30 39 of the second group selector, when the latter has been set on a definite contact group. In this case + pole of the battery is connected to lead 39 at the above second group selector, relay G energizes and over its contact 96g energizes relay HR through winding II.

If in most calling routes in an arrangement a definite number of numerical impulse trains are to be noncontrolling it is possible by setting up a suitable controlling device to allow a larger 40 number of numerical impulse trains to pass through the discriminator without controlling. This can also result by using a relay G, as in Figure 4, in which this relay on energizing disconnects the winding I of relay HR from contact 15, (Fig. 1) and connects it to a succeeding contact, for example contact 73, if a fourth impulse train is to be noncontrolling in this call direction, and thus connects contacts 15 and 74 with contacts 5v2 and 12v2. The energizing 50 of relay G can take place after the transmission of the second impulse train from the second group selector, or alternatively after the setting of the first group selector, through an off normal contact of this selection.

Having described the invention, what is considered to be new and is desired to be protected by Letters Patent will be set forth in the following claims.

What is claimed is:

1. In a telephone system, a trunk line, a discriminator switch in said trunk line responsive to a series of impulses transmitted over said trunk line to said switch, said switch operated in a definite manner independent of the number 65 of impulses in the series, switching means in said switch, means responsive to the termination of said impulse series for operating said switching means, and means responsive to the operation of said switching means for altering the operation 70 of said switch so that it will be operated directly under the influence of additional series of impulses.

2. In a telephone system, a trunk line, a discriminator switch in said trunk line responsive 75

to a plurality of series of impulses transmitted over said trunk line, said switch operated in a particular manner by a number of series of impulses independent of the number of impulses in the series, a relay in said switch, said relay operated responsive to the termination of said series of impulses, and means controlled by the operation of said relay for conditioning said discriminator switch to be directively operated by additional series of impulses in a manner in accordance with the impulses in the series

3. In a telephone system, a discriminator switch, a trunk line extending to said switch over which a plurality of series of impulses are transmitted to said switch, said switch operated responsive to said impulse series to advance two steps for each series of said impulses, and means operated responsive to the termination of said impulse series for conditioning said switch to operate responsive to further series of impulses in accordance with the number of impulses in the series.

4. In a telephone system, a trunk line, a discriminator switch in said trunk line responsive to series of impulses transmitted to said switch over said trunk line, said switch operated by said series of impulses one step at the beginning and one step at the end of the impulse series regardless of the number of impulses in the series, and means responsive to the termination of the impulse series for altering the operation of the switch so as to operate in accordance with the number of impulses of additional series of impulses.

5. In a telephone system, a trunk line, over which a plurality of series of impulses are transmitted, a discriminator switch in said trunk line, said switch operated by said series of impulses to advance one step at the beginning and one step 5 at the end of the impulse series regardless of the number of impulses in the series, means responsive to the cessation of the last impulse of the series for conditioning said switch for different operation, said switch thereby operated by additional 10 series of impulses to advance step-by-step in accordance with each impulse of the additional impulse series.

6. In a telephone system, a trunk line over which series of impulses including controlling and 15 non-controlling series are transmitted, a discriminator switch in said trunk line, said switch operated responsive to the reception of a non-controlling series of impulses to advance a definite number of steps regardless of the number of impulses in the series, switching means operated by said switch, said switching means altering the operation condition of said switch, and means responsive to the reception of a controlling series of impulses for advancing said switch in accordance 20 with the impulses of the controlling series.

7. In a telephone system as claimed in claim 2 in which the relay is connected to the position in the bank on which the switch has been positioned in order to condition the switch for the directive 25 reception of the impulse series.

WALTER PINELL.
